Application October 26, 1935, Serial No. 46,840
In Austria November 17, 1933

8 Claims. (Cl. 72—37)

This invention relates to dry masonry and to a practical method of building such masonry.

The main object of our invention is to make it possible to lay up courses or tiers of bricks and thereby construct masonry in dry form without using the usual mortar and thereby obtain a masonry structure which has, as a result, a very high compressive strength and satisfactory resistance to shearing and bending.

10 Another object is to produce dry masonry which is time and labor saving without sacrificing any of the advantageous characteristics desired in a good structure of this nature.

15 A very important object of the invention is to introduce between the tiers of the bricks mainly composing the masonry an intermediate joint material having considerably greater tensile strength and elasticity than the mortar which is ordinarily used in this art.

20 A further object is to utilize the intermediate joint material between the bricks in the form of webs, bands or slabs.

25 Yet another object is to use petrified wood wool, special webs of the same or of other material for the mentioned intermediate joint material.

30 Other objects and the various advantages inherent in the nature and practice of our invention will appear more fully in detail as this specification proceeds.

In order to render our invention readily comprehensible and assist in pointing its advantages, reference is now had to the accompanying drawing forming part hereof, in which

35 Fig. 1 illustrates a piece of masonry constructed according to the invention and embodying certain of its advantageous features.

Fig. 2 is a vertical section of the masonry shown in Fig. 1.

40 Figs. 3 and 4 are similar sections illustrating modifications.

Fig. 5 is an elevation of a modified masonry structure of compressed type.

Fig. 6 is a vertical section of the same.

45 Fig. 7 is an elevation of another modified masonry structure using surface plates.

Fig. 8 is a vertical section of the same.

Throughout the views, the same reference indicia refer to the same or like parts.

50 In ordinary masonry wherein mortar is used, it is well known that large quantities of water are unavoidably introduced into the structure during building, necessitating considerable loss of time for drying out the walls involved. It is also well known that building operations are sus-

pended altogether during frost and practically the entire winter season, due to the impossibility of mixing and working mortar at low temperatures. Many other disadvantages might be added.

5 However, in order to eliminate all such disadvantages, and particularly with the foregoing objects in view, it is now proposed to depart entirely from the usual practice of laying mortar between the bricks in masonry.

10 Hence, in the investigations leading up to our invention, we have found that the material introduced between the bricks or blocks in masonry structures should be capable of yielding slightly, in order to allow for the inequalities of the individual blocks, and on the other hand is of sufficient strength in the plane of the slab to withstand without breaking the strains set up in the material of the bed joints when stressed in compression. Tests carried out have unexpectedly 15 shown, that masonry constructed in this manner offers to thrusts and shearing forces not only an equal, but mostly a greater resistance than ordinary mortar masonry.

20 In the practice of this invention, it is particularly to be borne in mind that felt is not used as it is considered to be unsuited for the present purpose inasmuch as it is rather compressible and does not have tensile strength, firmness or resistance to shearing in any marked degree, and 25 we now depart herein from materials of that specific class.

25 However, investigation has shown that some materials of the fibrous nature are eminently suited to the purposes of the invention and have 30 exhibited very satisfactory results. Thus we have found that among other materials available upon the market, wood wool treated with petrifying or mineralizing substances will serve admirably and give excellent results. When using 35 such mineralized wood wool in the form of slabs or other suitable materials in useful form, the great advantage obtained is that the joint material can be readily adapted to special requirements for insulating against cold, heat, sound, 40 moisture, vibrations and the like.

45 In certain circumstances it may be desirable to provide the edges of the wood wool slabs with projecting thickenings. These provide the advantage, that when the courses are being laid, 50 the blocks are automatically brought into the correct position. If the wall is to be subsequently plastered, these projections offer a good hold for the plaster material; they may also be used for fixing facing plates, whereby a sound and heat 55

insulating layer of air can be produced in a very simple manner.

It is also possible to provide the outer edges of the slabs or bridging members with coloured cements or metal bindings (for instance aluminium foil), so that in addition to the protection of the slab material a novel internal or external architectural effect for a raw brick building is obtained.

10 The wall is given additional strength, if the courses of blocks be provided with vertically inserted and firmly interconnected reinforcing or locking members. In combination with the above described invention they provide special advantages, however, which are due to the fact that the joint material used in accordance with the invention always retains a certain elasticity, so that, in contradistinction to their use with non-elastic blocks and mortars, the state of compression in the masonry produced in clamping the reinforcing members, or the tension in the locking members is always maintained. Furthermore these locking members prevent an outward buckling of the slabs in parts of the masonry which are stressed in bending at right-angles to the wall surface, thus increasing the bending strength of the masonry.

Bearing the foregoing particulars in mind, we refer again more particularly to the drawing illustrating the invention.

The fragmentary elevation of Fig. 1 illustrates the typical appearance of a piece of masonry constructed according to the invention. Hence, between each two courses of the bricks *a* is interposed the novel joint material *b* (for instance mineralized wood wool slabs). The vertical joints of the bricks at *c* may, but need not necessarily be filled with wood wool slabs, slag wool pads or the like.

40 In Fig. 2 is shown a piece of masonry in section, having plaster *d* applied upon one side on the slightly projecting edges of the joint material *b* and on the other side a covering plate *e* which is nailed to the joint material and supports the plaster *d*.

Another typical application of the invention is illustrated in Fig. 3, which shows a construction in which the slabs of joint material *b* have thickened parts *f* at the edges serving on one side to support the plaster *d* and on the other side are covered with plates *g* in such a manner that an insulating air space *h* is formed between the covering plates and the masonry.

In Fig. 4 is shown a piece of masonry in section having the slabs of joint material *b* provided with metal framing *i* or pointed with decorative cement *k*.

The modified form of masonry construction shown in Fig. 5 illustrates how several courses 60 of bricks *a* are pressed together by locking members *l* with interposed joint material *b*. The locking members *l* are anchored in a concrete grid *m* on iron rails *n*.

In the detail modification of the construction 65 shown in Fig. 6 the locking members *l* are anchored in the concrete grid *m* on iron girders *n*.

The modified masonry construction appearing in Fig. 7 illustrates how in this form of the invention, the anchoring means *o* of the covering 70 plates *p* form the vertical locking members.

In Fig. 8 which shows a piece of masonry in section according to a further modification illustrating the anchoring means *o* of the covering plates *p*.

It has already been mentioned herein that the

preferred joint material is mainly composed of mineralized wood wool or slag wool, but in order to bind the same into preferred form of slabs or pads, known binders may be used which tend to harden or set for the purpose of retaining the fibres in their position in the slab. The resulting surface of the slab is preferably rough and therefore presents a very highly satisfactory degree of friction with bricks which are laid up in contact therewith.

10 While it has heretofore been the practice to fill the joints between bricks with mortar usually prepared with lime or similar binders and mixed with water, yet obviously this is wholly done away with when a wall does not have any mortar introduced into it but each course or tier of bricks is simply overlaid with a slab or pad of the present novel joint material and subsequent courses laid upon the same and the operation repeated. It is also obvious that the temperature 20 or season of the year will not affect the wall thus built and work may proceed rapidly.

Nevertheless, webs of woven material such as jute or slabs of fibrous material reinforced with wires or wire mesh or netting will also give good 25 results, so that these materials may be used instead of the mineralized wood wool.

In addition to the foregoing, it should be pointed out that while apparently it is not new to resort to the use of other filling materials than 30 mortar, it has hitherto been completely overlooked that the important feature which must be present is that great tensile strength and elasticity of the joint material introduced are essential in order to impart to the masonry such strength as to 35 equal the best mortared masonry when the proper selection of materials has been made. The surprising discovery has also been made that when materials having these characteristics and, in addition, having very high degree of friction with 40 the surface of the bricks, the resulting structure will present an astonishingly high resistance to buckling or bending.

While the invention has for the most part been 45 described as used in connection with bricks or blocks, it is obvious that in the appended claims bricks are equivalent to building stones, concrete blocks or other well known forms of building units used for constructing walls and masonry in general. Manifestly, further modifications and variations may be resorted to and certain features 50 may be used without others.

Having now fully described our invention we claim:

1. In dry masonry comprising a plurality of 55 superposed courses of bricks, preformed intermediate joint means interposed between said courses, said joint means comprising inherently firm joint material consisting of vegetable fibres associated with a setting binder retaining 60 said fibres structurally in position, the fibres and binder together serving to hold the bricks in association by friction and having great tensile strength, resistance to shearing and a general roughness imparting great compressive 65 strength to the masonry.

2. Dry masonry according to claim 1, wherein the joint material is formed into slabs provided with wire reinforcing insertions.

3. Dry masonry according to claim 1, wherein 70 the vegetable fibres in the joint material consist of wood wool, and joint material is formed into slabs provided with wire reinforcing insertions.

4. Dry masonry according to claim 1, wherein 75

the fibres in the joint material consist of mineralized wood wool, and the joint material is formed into flat slabs.

5. Dry masonry according to claim 1, where-
5 in the joint material projects exteriorly of the masonry between the courses in the form of thickened portions.

6. Dry masonry according to claim 1, wherein the joint material projects exteriorly of the masonry between the courses in the form of thick-
10 ened portions upon one side and a decorative facing is applied to the joint material on the other side of said masonry.

7. Dry masonry according to claim 1, where-

in the joint material consists of a woven web of vegetable fibres reinforced with wire reinforcing insertions.

8. Dry masonry according to claim 1, where-
in a plurality of elongated reinforcing and locking members are built into the masonry structure, each of said reinforcing and locking mem-
bers extending past a plurality of the individual bricks in said structure and serving to lock the same into a dry masonry structure under a pre-
10 determined constant degree of compression.
